Primary Examiner — Mojtaba Tehrani(74) *Attorney, Agent, or Firm* — Jose Cherson Weissbrot(57) **CLAIM**

The ornamental design for an air compressor manifold, as shown and described.

DESCRIPTION

FIG. 1 is a front perspective view of an air compressor manifold, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a rear perspective view thereof; and,

FIG. 9 is an another perspective view showing the air compressor manifold, in used condition.

All the broken lines in the drawings depict portions of the air compressor manifold that form no part of the claimed design.
